(57) **CLAIM**

The ornamental design for a wand, as shown and described.

DESCRIPTION

FIG. 1 is a perspective view of a wand of the new design;

FIG. 2 is another perspective view of the wand of FIG. 1;

FIG. 3 is a top plan view of the wand of FIG. 1;

FIG. 4 is a rear elevational view of the wand of FIG. 1; and,

FIG. 5 is a front elevational view of the wand of FIG. 1, the left side elevational view and the right side elevational view being a mirror image thereof.

The portions of the Figures shown in broken lines are not part of the claimed design and are for illustration only.
